UNITED STATES PATENT OFFICE.

FRANZ RAWIE, OF OSNABRUCK-SCHINKEL, GERMANY.

RAILROAD BUFFER CONSTRUCTION.

Application filed July 2, 1923. Serial No. 649,112.

To all whom it may concern:

Be it known that I, FRANZ RAWIE, a citizen of the German Republic, residing at Osnabrück-Schinkel, Germany, have invented certain new and useful Improvements in Railroad Buffer Constructions (for which I have filed patent application in Germany July 5th, 1922), of which the following is a specification.

10 This invention refers to such railroad buffer constructions in which the buffer is adapted to make a sliding movement in the direction of the rails against the resistance of a packing of sand, pebbles, gravel or the like provided in front of same, and it is intended to provide means for increasing the resiliency and reliability of operation of devices of this kind, and to generally improve the construction and operation of the same.

15 Whenever it is desired to produce a steady and not dangerous braking action by means of a packing of sand, gravel or the like, it is of paramount importance that such material, sand or the like, should be caused to press with uniform pressure against a surface of a certain determined area corresponding to the value of the desired braking resistance, when the buffer is displaced relatively to the track. It is necessary, therefore, to provide the buffer with a front beam adapted to bear against the packing and to push the same in the forward direction. During this action the buffer, in order to produce a regular reliable braking action, should be free to move relatively to the track without being able to be raised off from the same, inasmuch as the raising off of the buffer is known to be the preamble to the climbing and as a result thereof of the de-

20 railment of the cars. In view thereof my invention provides means for mounting the buffer so as to be freely displaceable upon the track the buffer being merely provided with claw shaped guiding means engaging

25 below the head of the rails, and adapted to prevent the raising off of the buffer from the track. Other details of construction designed to insure the reliability of operation in the practice of my invention, and other

30 advantages will appear from the detailed description of the embodiment of the principles of my invention shown on the accompanying drawings by way of example, Fig. 1 showing a buffering device according to my invention in side elevation and partly in section. Fig. 2 is a plan of the same, Fig. 3

is a section along the line 3—3 of Fig. 1, and Figs. 4 and 5 are a vertical section and a plan, respectively, of a modified form of thrust plate structure.

60 The buffer construction comprises as usually a thrust triangle 1, 2, 3 and a thrust sleeper 4. It is displaceably mounted upon the rails 5 the heads of which are embraced by claws 8 provided on one side of the metal sheets 6, 7 connecting the side bars 1 and 2 of the thrust triangle. The claws 8 are arranged on one side of the sheet metal plates 6, 7 only for the reason to allow of being able to connect the ends of the rails by fish plates at least at one side even at the section of rails over which the buffer is going to pass in its movement.

70 Upon its front side the buffer is provided with a front thrust beam which in the construction shown by way of example in the drawing is made in two sections, and comprises a U-shaped beam 9 and an adjustable thrust plate 10 mounted thereon. The vertical adjustment of the plate 10 relatively to the beam 9 may be effected by providing the web portion of the U-shaped beam 9 at different levels with holes 11 through which bolts or the like 12 secured in apertures of the plate 10 may be passed. The vertical adjustment of the plate 10 is intended to provide for the adaption of the structure to varying braking resistances which may be desired according to local and other requirements. 13 indicates a packing of sand or the like placed upon the road bed.

75 When a train or a car moves against the buffer the thrust will cause the buffer to be displaced towards the packing 13, the material of the packing either giving way laterally or being pushed over the front beam 9, 10 and being spread upon the track, so that to the braking resistance presented by the bulk of the packing 13 there is added the well known resistance presented by a sand packing upon the track. The possibility of freely displacing the buffer relatively to the track results in the particular important advantage that the entire buffering structure even after repeated thrust of a moving train or engine against it, and after its displacement is still ready for immediate operation, inasmuch as there will merely be a change of the particular point at which the braking of the movement of the train takes place in accordance with the displacement of the buffer along the track.

In case of absorbing considerable moments of forces which is only attainable by displacement through a large distance it is preferable to provide means that the sand or the like of the packing is wholly or in part pushed sideways. With this point in view the front thrust beam 9 upon its entire extent or for only part of its height may be arranged at an angle to the direction of displacement of the buffer. The inclination of the front thrust beam with relation to the direction of displacement may also be produced by imparting to said beam a substantially angular shape with forwardly directed pointed portion.

In order to make provision for the possibility that in cold weather the packing which is to constitute the braking resistance becomes frozen so as to exclude the possibility of regulating and controlling the braking resistance the arrangement may be such that the buffer is provided not only with the front thrust beam mentioned the height of which governs the braking resistance of the packing but with a scraper or push beam at an angle to the vertical beam and projecting beyond the upper edge of the same. Such modified form of a thrust wall structure is illustrated in Figs. 4 and 5. The front beam 9^a and the thrust plate 10^a are both angle shaped with a point 14. The scraper at the upper edge of the thrust plate is designated 15; and is fixed at its lower edge to flaps 16 and at its upper edge to flaps 17, the flaps 16, 17 being formed by working slots into the upper edge of thrust plate 10^a and by suitably bending the portions between said slots. Experience has shown that the material of this kind of sand packing or the like is only superficially frozen to a solid mass even in the coldest weather. If therefore the front thrust beam with its upper edge is below the frozen mass of the packing it encounters substantially a rather uniform resistance. In order to arrive at this result, it is, therefore, only necessary to provide means for suitably removing the frozen layer of packing remaining above the front thrust beam, which may be effected by the scraper or push beam or the like above referred to, and it is possible in this manner to arrive at the desired regular braking even in frosty weather and with a consequently superficially solidly frozen packing.

55 The invention has been described merely in one of its possible exemplifications, but without restricting the invention thereto,

and it should be understood that there may be other modifications and changes to suit existing conditions, and without deviating from the spirit of my invention as pointed out in the claims.

What I claim is:—

1. In a buffing device the combination with a track and a packing deposited thereon of a buffer proper slidably but undetachably mounted on the rails of the track and provided with a thrust wall bearing against said packing deposited on the track in front thereof.

2. In a buffing device the combination with a track of a buffer proper slidably but undetachably mounted on the rails of the track and provided with a thrust plate in front thereof, the thrust plate comprising an adjustable member allowing height adjustment of the upper edge of the thrust plate with relation to the track.

3. In a buffing device the combination with a track of thrust receiving means slidably secured on said track comprising a thrust plate in front thereof and scraping or clearing means adapted to displace an upper layer of packing material deposited on the track in front of said thrust plate on sliding displacement of said thrust receiving means on the track.

4. In a buffing device the combination with a track, of thrust receiving means slidably but undetachably mounted on said track provided with a substantially vertically arranged thrust plate and with an inclined portion at the upper end thereof extending beyond the upper edge thereof adapted to engage an upper layer of packing material deposited on the track.

5. In a buffing device the combination with track forming rails connected at abutting ends by fish plates at one side only, of thrust receiving means slidably but undetachably mounted on said rails, guides on said thrust receiving means engaging said rails on the side opposite the fish plate carrying side, the thrust receiving means provided with a thrust plate in front thereof.

6. In a buffing device the combination with a track of a buffer proper slidably but undetachably mounted on the rails of said track and provided with a thrust wall arranged obliquely to the direction of said track.

In testimony whereof, I affix my signature.

FRANZ RAWIE.
